DESIGN FOR A TRICYCLE

George Lewinski, Toledo, Ohio, assignor to The American-National Company, Toledo, Ohio, a corporation of Ohio

Application June 5, 1939, Serial No. 85,354

Term of patent 7 years

To all whom it may concern:

Be it known that I, George Lewinski, a citizen of the United States of America, residing at Toledo, in the county of Lucas, in the State of Ohio, have invented a new, original, and ornamental Design for a Tricycle, of which the following is a specification, reference being had therein to the accompanying drawing, forming a part thereof, wherein:

I claim:

The ornamental design for a tricycle, substantially as shown.

GEORGE LEWINSKI.
